ELEVATOR APPARATUS

Arthur K. Tylee, Brookline, Mass.

Application August 26, 1931, Serial No. 559,370

7 Claims. (Cl. 187—52)

My invention relates to door mechanisms for elevator apparatus of that class wherein an elevator landing door or gate at a landing is automatically opened when the car of the elevator is at said landing and automatically closed before the car is started to move to another landing.

My invention has for its object to provide an improved door mechanism of the character described.

10 Apartment houses and other buildings have heretofore been provided with electrically operated elevator apparatus including a system of push-buttons by means of which the car was controlled by the passengers, and it has heretofore been customary to construct the car of an elevator apparatus of this type with a sliding door which was automatically opened upon arrival of the car at its destination and which was automatically closed. My invention may be, and 15 preferably is, embodied in an elevator apparatus constructed and operating in this fashion.

Also, it has heretofore been customary to provide the elevator landing doorway with a sliding door which was directly engaged by the car door so as to be opened and closed by and with the latter, the movement of the car into position at a landing serving to couple the two doors so that they were simultaneously opened and closed by the same door operating means, the latter usually comprising an automatically controlled electric motor mounted on the car and connected with the sliding door of the latter.

In carrying out my invention I provide a door or gate at the landing which is pivotally supported as by hinges to swing laterally into and out of its closed position, and means is provided through which the operation of an element or member that is movably mounted upon the car of the apparatus, preferably the door of the car, occasions a swinging opening movement of the pivoted well door or gate when said element or member is shifted (however motivated) on the car in one direction while the car is positioned at said landing, and through which said member or element occasions a swinging closing movement of said landing door or gate when said element or member is shifted on the car in the opposite direction.

In the best form of my invention the hinged laterally supported landing door or gate can also be tilted laterally toward and from the well thereby to shift its center of gravity so that it is opened and closed by gravity instead of by power transmitted to it from the car door as has heretofore been the case.

It is also a feature of my invention, in its best form, that while the landing door or gate is opened and/or closed independently by gravity, it may be tilted in one direction to occasion an opening movement thereof by the car door when 60 the latter is moved into its open position, and in the opposite direction to occasion a closing movement thereof by the car door when the latter is moved into its closed position.

Thus, if the car door is automatically controlled and operated as described above, or manually operated, its opening and closing movements will occasion, and be accompanied by, the automatic operation of the landing door.

Other features of my invention are herein- 70 after pointed out.

In the accompanying drawings:

Figure 1 is a plan view of a portion of an elevator well showing also a portion of an elevator car disposed therein.

Figure 2 is a sectional detail hereinafter described.

Figure 3 is a section on line 3—3 of Fig. 1, but with the landing door 49, hereinafter described, removed.

Figure 4 is a diagrammatic view including a portion of the sliding car door, the door operating electric motor, and a portion of the circuit of the latter.

Figure 5 is a section on line 5—5 of Fig. 3.

Figure 6 is a section on line 6—6 of Fig. 3.

Figure 7 is a section on line 7—7 of Fig. 3.

Figure 8 is a section on line 8—8 of Fig. 3.

Figure 9 is a section on line 9—9 of Fig. 3.

In the accompanying drawings, 10 indicates a shaft or well and 11, 12 and 13 three of the walls thereof. Within this well 10 is disposed an elevator car 14 that is movable vertically on ways or guide rails provided upon the opposite side walls 11 and 13, one of said ways or rails being shown 95 at 15.

Journalized in bearings provided on the top of the frame of car 14 is a shaft 16 having fixed thereon a depending arm 17 whose lower end is pivotally connected with one end of a rack bar 18 that is supported or held in mesh with a pinion 19 by a yoke member 20. The yoke member 20 is pivotally hung upon the armature shaft of an electric motor 21 and the pinion 19 is fixedly 105 mounted upon said armature shaft.

The shaft 16 also has fixedly mounted upon it a depending longer arm 22 whose lower end is connected by a link 23 with a door 24 movably mounted upon the car 14 and controlling 110

the passage or doorway of the car through which the passengers enter and leave the car.

The car door 24 is supported, as usual, by rollers 25, Fig. 3, resting upon a horizontal rail 26 forming part of the frame of the car, said rollers 25 being connected by brackets with the top portion of door 24. In Fig. 1 the rolls; their brackets, and the rail 26, are omitted for clearness of illustration.

- 10 The car 14 may be operated by means of the usual electric push-button control system whereof some of the push-buttons are disposed within the car 14 and are used by the passengers to start the car upwardly or downwardly while the other 15 push-buttons are located at the landings and are used by would-be passengers to bring the car to one or the other of said landings corresponding with the landing button that is operated.

When a landing button is operated and the car 20 14 arrives and stops at that landing, the circuit of motor 21 is automatically closed and the rotation of pinion 19 then acts through rack-bar 18, arm 17, shaft 16, arm 22 and link 23 to move the door 24 from its closed position, shown in 25 the drawings, edgewise into its open position. As said door 24 reaches its fully open position it strikes the movable spring-pressed member of a normally closed switch 27 and opens the latter. This switch is in circuit with motor 21 as shown 30 in Fig. 4 and therefore said motor is automatically stopped by the door as the latter reaches its fully open position.

The door 24 is automatically locked in its open position by the usual spring-pressed latch 28 35 pivotally mounted on the frame of car 14, said latch engaging a toothed rack 29 carried by door 24 as the latter nears the limit of its opening movement.

The latch 28 is connected by a link 30 with 40 the core 31 of a solenoid 32, the latter being energized when one of the buttons within the car or a landing button is operated to start the car upon its travel from one landing station to another. When solenoid 32 is thus energized it acts through core 31 and link 30 to swing latch 28 out of engagement with toothed rack 29 whereupon the usual car door counter-weight 33, Fig. 1, acts to close door 24.

Counter-weight 33 is mounted to move vertically in ways on the frame of the car and has fastened to it one end of a flexible cable 34 which extends upwardly therefrom, over a sheave 35 mounted on car 14, to door 24 to which its opposite end is fastened. This counter-weight mechanism is as usual and is omitted from Fig. 3 for the sake of clearness.

As the car door 24 is moved into its fully closed position the car operating motor of the apparatus is automatically started through the usual means, not shown.

When the car 14 reaches the landing which is its destination it is automatically stopped by the usual means, not shown, and then the motor 21 is automatically started to open the car door as 65 already described.

The above described construction and operation is as usual in elevator apparatus of this type.

At a landing 36, Fig. 3, the wall 12 of the well 10 is made with a doorway 37 within which is fixed a rectangular metal frame comprising a top channel-iron cross-bar 38; two vertical channel-iron side bars 39 and 40, and a sill plate 41. The flanges of the channel-iron bar 39 are disposed upon the inner side of the latter and between these flanges is arranged a door-support-

ing member 42 consisting of a bar of channel-iron that is slightly less in length than the distance between the top cross-bar 38 and sill plate 41.

Approximately midway between its opposite ends the door-supporting member 42 is provided upon its inner side with a bracket 42a, Figs. 6 and 7, having an aperture formed therethrough within which is provided a ball bearing 43 that surrounds a stud 44 projecting from another bracket 45 secured to the web of the side bar 39 of the frame of the doorway. A nut 46 applied to the outer threaded end of the stud 44 holds the bracket 42a in position upon said stud.

The stud 44 serves to pivotally support the member 42 within the side bar 39 of the door frame and the engagement of the ends of said member 42 with the flanges of side bar 39 serves to limit the tilting movement of member 42 on stud 44.

To the member 42 are secured two hinge leaves 47 and 48 whose complementary leaves (which are removed in Fig. 3) are secured to one side of a door 49 as shown in Fig. 2.

Within the side bar 39 and near the upper end thereof is mounted a spring 50, Figs. 3 and 5, whereof one end bears against member 42 and the opposite end against one of the flanges of side bar 39. This spring normally holds the member 42 with its upper portion tilted toward the well 10 so that the door 49 is held by gravity in its closed position where it rests against a stop or abutment strip 51, Fig. 1 which limits the swinging movement of the door toward the well 10.

Near its lower end the door-supporting member 42 has fixed upon its inner side a bracket 51 carrying an anti-friction roller 52 that bears against the web of side bar 39 so as to hold member 42 out of contact therewith.

Extending through an aperture provided in the inner flange of side bar 39 near the upper end thereof is a slide bar 53 whose inner end is pivotally connected with member 42 and whose outer end is within the well 10 and carries a roll or truck 54 to co-operate with a cam plate 55 mount- 115 ed upon the car door 24.

When the car 14 comes into position and stops opposite the landing 36 the cam plate 55 is in the same horizontal plane with the slide-bar 53 as shown in Fig. 3. It will therefore be clear that 125 the opening of the car door 24, which may occur as soon as the car stops at the landing, causes the cam plate 55 to act through the slide-bar 53 to swing the door-supporting member 42 and the door 49 on the axis of the stud 44 so as to 130 tilt the upper portion of the door away from the well 10. When the door is thus tilted outwardly at its upper end its center of gravity is shifted with respect to the hinges so that gravity acts thereon to swing the same into an open position 135 where it is approximately at right angles with the wall 12 as shown in Fig. 2.

With the construction herein illustrated the doors 24 and 49 remain open as long as the car 14 remains at the landing, but this is not essential since obviously provision may be made for allowing the car door to close automatically after being held opened a predetermined length of time. When the apparatus, constructed as herein shown, is operated to start the car on its travel either upwardly or downwardly and the car door 24 is closed as described, the cam plate 55 is moved out of engagement with the slide-bar 53, whereupon the spring 50 tilts the upper portion of member 42 and door 49 inwardly toward the well 10. 150

If the door 49, when in its fully open position, is perpendicular with respect to the wall 12 as shown in Fig. 2, it is desirable to provide means to give an initial closing impulse to the door to start it upon its swing toward well 10. As herein shown this means may include a bracket 56 fastened to the inner flange of side bar 39 near the lower end thereof, to which bracket is pivotally connected one end of a piston rod 57 provided at its opposite end with a piston 58 arranged within a cylinder 59.

This cylinder 59 has one end thereof pivotally connected at 60 with a bracket 61 fastened to one side of the door 49 near the bottom of the latter.

15 Within the cylinder 59 is arranged a coiled spring 62, one end of which co-operates with the piston 58 and the opposite end of which bears against one end of the cylinder 59.

In Fig. 2 the parts are shown in the positions they occupy while the upper portion of door-supporting member 42 is held tilted outwardly by the cam 55. With the parts in these positions the spring 62 is under little or no compression and therefore the door 49 is held by gravity in its fully 25 open position.

When the door 24 of the car is closed and cam plate 55 is moved out of engagement with the slide-bar 53, the spring 50 tilts the upper portion of member 42 and door 49 inwardly toward 30 the well 10, the lower portions of said member and door being moved outwardly away from well 10 because of the fact that the member 42 is pivotally supported at its middle by the stud 44.

When the lower end portions of member 42 and 35 door 49 are thus moved outwardly away from well 10 and relatively to side-bar 39 and bracket 56, Fig. 2, the cylinder 59 moves with the door 49 and the spring 62 thereby is compressed and acts through the cylinder 59 to start the door 49 on its 40 swing toward closed position. The spring 62 need impart but slight movement to the door 49 after which gravity carries the door into its fully closed position against the abutment strip 51.

45 It is customary, in semi-automatic elevator apparatus including push-button control mechanism, to provide a latch by which the landing door is held in its closed position but which is automatically operated to free said door when the car stops at a landing and its door 24 is open. In Fig. 1 of the drawings I have indicated by dotted lines at 63 a latch of the kind referred to which is normally held by a spring, not shown, in position to lock the door 49 in its closed position. This latch 63 is connected by means of a bell crank lever 64 with a slide-bar 65 carrying a truck or roll 66 to co-operate with a device 67 that is carried by the counterweight 33. When the door 24 is opened upon arrival of the car 14 at a landing where said car is stopped the counterweight 33 is raised as above described and the device 67 is operated to act through the slide-bar 65 and bell crank 64 to retract the latch 63 and free the door 49. This unlatching of the door 49 may occur as the door 24 nears the limit of its opening movement. The only difference between this latch mechanism for the door 49 and mechanisms for this purpose as heretofore provided is that the latch member or bolt 63 is in the same horizontal plane with the pivotal stud 44. Otherwise this mechanism is constructed and operated by the counterweight 33 as usual.

The mechanism for operating the car 14 and by which it is raised and lowered within the well or shaft 10 is omitted from the drawings, but is

as usual and as usual is controlled by the push-button system of the apparatus.

It is to be understood, however, that while I have herein described the car as controlled by means of push-buttons, the car 14 may be controlled and operated through any suitable mechanism.

What I claim is:

1. In an elevator apparatus, the combination with a car provided with a door that occupies a closed position while said car is in motion and which is opened when said car is at a landing, of a well provided with a doorway at said landing; a movably supported door for said doorway, and means through which said car door when opened while the car is at said landing adjusts said movably supported landing door thereby to cause the latter to be opened by gravity and through which said car door when closed while said car is at said landing adjusts said landing door thereby to cause the latter to be closed by gravity.

2. In an elevator apparatus, the combination with a car provided with a door that occupies a closed position while said car is in motion and which is opened when said car is at a landing, of a well provided with a doorway at said landing; a door for said doorway; a movably supported hinge connected with and supporting said last mentioned door, and means through which said car door when opened while the car is at said landing acts to adjust said hinge so that said landing door is opened by gravity and through which said car door when closed while said car is at said landing acts to adjust said hinge to cause said landing door to be closed by gravity.

3. In an elevator apparatus, an elevator well provided with a landing and having a doorway at said landing; a door-supporting member movably mounted within said doorway at one side of the latter; a door for said doorway hingedly connected with said door-supporting member, and means adapted to be operated by the door of a car to adjust said door-supporting member thereby to tilt said door so that it is opened by gravity when the car door is opened and is closed by gravity when the car door is closed.

4. In an elevator apparatus, an elevator well provided with a landing and having a doorway at said landing; a pivotally supported door-supporting member adjacent one side of said doorway; a door for said doorway hingedly connected with said door-supporting member; a spring for tilting said door-supporting member and its door in one direction to cause said door to be closed by gravity, and means through which the door of a car when opened while said car is at said landing acts to tilt said door-supporting member and its door in the opposite direction to cause said tilted door to be opened by gravity.

5. In an elevator apparatus, the combination with a car having a door and a cam on said door, of an elevator well provided with a landing and having a doorway at said landing; a pivotally supported door-supporting member adjacent one side of said doorway; a door for said doorway hingedly connected with said door-supporting member; a spring for tilting said door-supporting member and its door in one direction to cause said door to be closed by gravity, and means through which said cam acts to tilt said door-supporting member and its door in the opposite direction when said car door is opened thereby to cause said tilted door to be opened by gravity.

6. An elevator apparatus constructed in accordance with claim 2 wherein there is also pro-

vided means for imparting an initial closing impulse to said door when said hinge is adjusted to cause said landing door to be closed by gravity.

7. An elevator apparatus constructed in accordance with claim 2 wherein there is also provided means for imparting an initial closing impulse to said door when said hinge is adjusted to

cause said landing door to be closed by gravity, said means comprising a normally inert spring that is stressed when said hinge is adjusted to effect the closing of the door that is supported by it.
